UNITED STATES PATENT OFFICE

GRECI G. GOMEZ, OF JOHNSONBURG, PENNSYLVANIA

GRAPHITE ANODE

Application filed August 25, 1930. Serial No. 477,667.

This invention relates to anodes and more particularly to a novel anode for use in electrolysis of brine.

One of the primary objects of my invention is to provide novel means for constructing an anode used in electrolysis of brine which has produced more rapid immigration of the chlorine and sodium atoms, which means lower voltage and more production and which will effectively withstand the action of the electrolyte and thereby give great length of service.

Another salient object of my invention is the provision of a graphite anode arranged in a novel manner between a pair of depending electrodes, with novel means for connecting the electrodes to the anode so that the electrolyte can not affect said connecting means.

A further important object of my invention is to provide an improved anode of the above character, which will be durable and efficient in use, one that will be simple and easy to manufacture, and one which can be placed upon the market at a low cost.

With these and other objects in view, the invention consists in the novel construction, arrangement and formation of parts, as will be hereinafter more specifically described, claimed, and illustrated in the accompanying drawing, in which drawing:—

Figure 1 is a side elevation of my improved device.

Figure 2 is a front elevation of the same showing parts thereof broken away and in section and illustrating the novel means employed for uniting the electrodes with the anode.

Figure 3 is a top plan view of my improved device.

Referring to the drawing in detail, wherein similar reference characters designate corresponding parts throughout the several views, the letter A generally indicates my improved device which comprises an anode 5 centered between a pair of depending electrodes 10 and 11. The anode 5 is formed from graphite in accordance with my invention, while the plates or electrodes 10 and 11 can be formed from any desired material. The

anode 5 includes an enlarged centrally disposed body portion 6, with which the electrodes or plates 10 and 11 facially abut and the upwardly extending reduced post 7. The body 6 of the graphite anode 5 is provided with horizontally extending spaced openings 8, which register with openings 12 and 13 formed in the upper ends of the electrodes or plates 10 and 11. These registering openings 8, 12, and 13 receive hard rubber sleeves 14 through which extend the fastening bolts 15, the heads and nuts of the bolts are countersunk within the electrodes or plates 10 and 11 and the countersunk portions are filled with mestic or similar substance to prevent the brine from coming into contact with the brass fastening elements 15. The mestic is indicated by the reference character 16. The post 7, at its point of juncture with the body 6 of the anode 5 can receive a hard rubber jacket 17, so as to protect the anode from the action of the brine or electrolyte.

My improved anode is particularly adapted to be used in gas cells with chlorine and sodium chloride. These cells are used and equipped for use in a bleach plant in the manufacture of pulp for paper and other manufactured productions. The anodes, now in general use, quickly deteriorate and I have produced a graphite anode that will have wearing quality several times greater than the anode now in general use.

Changes in details may be made without departing from the spirit or scope of this invention.

What I claim as new is:

1. A device of the character described comprising a central graphite anode including a body and a reduced post, electrodes having their extreme upper ends in facial abutment with the opposite sides of the body and depending therefrom for a material distance, the body and upper ends of the electrodes provided with registering openings, sleeves of insulation fitted in said registering openings, fastening bolts extending through the sleeves for connecting said electrodes to the anode, the terminals of the fastening elements being countersunk within the electrodes, mestic covering the terminals of said

fastening elements, and a jacket of hard rubber engaging about the post at the point of connection thereof with the body.

2. A device of the character described comprising a comparatively short centrally disposed anode, including a body and a reduced post formed of graphite, a plurality of relatively long depending flat electrodes arranged in parallel relation and projecting beyond the sides of said anode, said electrodes having the extreme upper ends thereof in facial abutment with the opposite sides of the body portion of said anode, means connecting the electrodes and body portion together, and means for protecting said connecting means against the action of the electrolyte.

In testimony whereof I affix my signature.

GRECI G. GOMEZ.
